UNITED STATES PATENT OFFICE.

EMIL GMINDER, OF REUTLINGEN, GERMANY.

METHOD OF AND APPARATUS FOR OBTAINING FIBER MATERIAL FROM STALKS.

Application filed March 10, 1927, Serial No. 174,307, and in Germany March 13, 1926.

My invention relates to improvements in the method of and apparatus for obtaining fiber material from stalks, and more particularly in the method in which the fiber material is obtained from the dry stalks. For stretching the material between rollers it is necessary that the length of the sections of the cut stalks is smaller than the distance between pairs of cooperating drawing rollers. In my improved process the stalks together with their leaves and seeds are continuously cut into pieces of the desired length, which length is smaller than the distance between the pairs of cooperating drawing rollers, whereupon the stalks are broken, beaten and afterwards cleaned for separating the fiber from the other parts such as wood, the whole operation on the stalks being performed before otherwise mechanically treating the same. After having cut the stalks into pieces of the desired length the said pieces are separated into different masses one mass comprising the pieces which are suitable for direct further treatment, and which are taken from the stalks proper, while the other mass comprises the pieces containing the heads, seeds and leaf portions of the stalks, and which therefore are unsuitable for being directly subjected to the further treatment. The said pieces which are not suitable for direct further treatment are first passed through a thrashing machine, whereupon they are combined with the directly suitable material for being subjected therewith to the further treatment.

For carrying out my improved method I make use of an apparatus comprising a pair of endless conveyer tapes each composed of a plurality of parallel sectional tapes and having cooperating branches tapering from their intake end towards their delivery end, the said operative branches being adapted to convey the stalks supplied thereto in transverse direction to disintegrating apparatus such for example as cutting blades or saws intersecting the said tapes and disposed between the sectional tapes. Preferably the upper branch of the lower tape is supported on a rigid table formed with slots for the passage of the saws or blades therethrough. Below the delivery end of the said conveyer tapes there are conveying bands which are preferably disposed transversely of the conveyer tapes and in alignment with each other and which extend from a median part of the said delivery end outwardly and to opposite sides, the said bands being driven so that the upper

branches thereof move outwardly from the said median part of the delivery end. The said bands are adapted respectively to receive the portions of the stalks which are suitable for direct further treatment, and the heads and other parts which are not suitable for direct further treatment, the first-named portions being carried by their conveyer band to the breaking, beating and cleaning apparatus, while the last-named portions are first passed through a thrashing machine.

For the purpose of explaining the invention an example embodying the same has been shown in the accompanying drawing in which the same letters of reference have been used in all the views to indicate corresponding parts. In said drawing,

Fig. 1, is a diagrammatical elevation showing the conveyer tapes and the conveyer bands disposed transversely below the same, and

Fig. 2, is an elevation looking from the right in Fig. 1 and showing in addition breaking and beating means.

In the example shown in the figures my improved apparatus comprises a pair of cooperating conveyer tapes 9 and 10 each composed of six sectional conveyer tapes having received in Fig. 2 the reference characters I, II, III, IV, V and VI. The lower tape 9 is trained on a driving drum 2 and a loose drum 1, and the upper conveyer tape is trained on a driving drum 3 and a loose drum 4, drums 5 and 6 being provided for putting the tapes under tension. The drums 1 and 2 are provided at their ends with flanges 12 adapted to hold the individual tapes in position. The direction of the movement of the tapes has been indicated in Fig. 1 by arrows α , and as shown, the cooperating branches of the tapes taper inwardly from the intake end towards the delivery end thereof, thus providing a mouth adapted to receive the stalks. Below the upper branch of the lower tape 9 there is a table 8 provided with longitudinal grooves or made in sections placed one beside the other and corresponding in breadth to the breadth of the sectional tapes I—VI. On the said tables cutting members such as disk-shaped saws 7 are mounted, which extend upwardly through the table 8 and between the spaces provided between the sectional tapes. At the rear of the table 8 and the saws 7, the tapes 9 and 10 approach each other more and more, and finally, both tapes are passed over the drum 2. In the example

shown in the figures the axes of the drums 2 and 3 are disposed at the same height; but I do not limit myself to this feature. In the preferred construction the distance between the tapes 9 and 10 moving over the drums 2 and 3 is equal to the thickness of the stalks. But I do not limit myself to this feature.

Below the drums 2 and 3 there are two transverse conveyer bands 13 and 14 which 10 are in alignment with each other and extend from a median part of the said delivery end inwardly. The said bands are driven by suitable mechanism so that their upper branches travel outwardly and in opposite 15 directions as has been indicated by the arrows p^1 and p^2 . As shown, the adjacent or intake ends of the bands 13 and 14 are located below the left part of the tapes 9 and 10, and the stalks are placed on the tape 9 so that the 20 heads and seeds are located at the left-hand side of Fig. 2 and delivered therefrom to the conveyer band 14 for being carried thereby to the left, while the cut stalks are delivered to the conveyer band 13 for being carried 25 thereby to the right. At the delivery end of the band 13 there are pairs of breaking rollers 15 and 16, and at the rear thereof a beater or scutching apparatus 17 which is preferably in the form of a Crighton opener, and 30 which is provided with a conical foraminated drum carrying pins 18.

Below the drums 2 and 3 and between the intake ends of the bands 13 and 14 there is a rockable gate 19, which is adapted to be 35 rocked more or less from its vertical position to the right or left for directing the cut pieces of the stalks to the bands 13 and 14. At the delivery end of the conveyer band 14 there is a thrashing machine 30, a roller 20 being provided above the said delivery end 40 for throwing the material into the thrashing machine. Preferably the said thrashing machine 30 consists of a beating drum 21 carrying ribs or spikes 26 and cooperating with 45 ribs or spikes 22 carried by the wall of the casing enclosing the said drum. At the bottom of the said machine there is a grate 23 and below the band 14 there is a conveyer band 24 extending from the outlet of the 50 thrashing machine to the intake end of the bands 13 and 14. Above the intake end of the band 13 there is a roller 25.

In the operation of the apparatus the stalks 55 are placed transversely on the intake part of the conveyer band 9, and they are carried thereby into the mouth provided between the tapes 9 and 10 and into position for being cut by the saws 7. The gate 19 is placed so that the pieces of the stalk proper drop on the 60 conveyer band 13, while the head parts of the stalks comprising the seeds and the leaves are passed on the band 14. The pieces falling on the band 13 are directly transmitted to the rollers 15 and 16, and from the latter to the 65 breaking or scutching drum 17, the distribu-

tion of the pieces of the stalks being regulated by means of the gate 19. Within the scutching drum 17 the scatcher acts on the pieces of the stalks and removes most of the woody particles previously broken by the breaking 70 rollers 15 and 16. In this operation the pins 18 have a carding action.

The head pieces falling on the band 14 are passed below the roller 20 and into the thrashing apparatus 30 in which the seeds 75 and leaves are removed by means of the spikes or ribs 26 and 22 and delivered through the grate 23, while the stalks are ejected in the direction of the arrow p^3 and between the conveyer bands 14 and 24 for being carried 80 thereby to the right and in the direction of the arrow p^4 . Finally the said thrashed portions pass between the roller 25 and the intake end of the band 13 by means of which they are carried to the breaking rollers 15 85 and 16 and the following apparatus. Thus the said thrashed stalks are broken, beaten and cleaned together with the pieces which have been directly carried to the said apparatus.

While in describing the invention reference has been made to a particular example embodying the same I wish it to be understood that my invention is not limited to the method and apparatus described herein, and that various modifications may be made in the operation and the general arrangement of the apparatus and the construction of its parts without departing from the invention.

I claim:

1. An apparatus for making fiber material from stalks including a plurality of saws mounted in spaced axial alignment, means for conveying stalks sidewise past said saws to cut the stalks into sections of a length less than the maximum distance between the co-operating pairs of drawing rollers, a conveyor movable in a direction parallel to the axis of said saws for receiving said sections and breaker rolls to which said conveyor delivers 105 said sections endwise.

2. An apparatus of the class described including a plurality of parallel saws, means for conveying stalks sidewise past said saws to cut the stalks into sections of a length less than the maximum distance between the co-operating pairs of drawing rollers, a conveyor movable in a direction parallel to the axis of said saws for receiving said sections and conveying them endwise, breaker rolls 115 into which said sections are delivered endwise by said conveyor, and scutching means for receiving said sections from said breaker rolls.

3. An apparatus of the class described including a conveyor for moving stalks endwise, means in the path of movement of said stalks for subdividing them into sections of a length less than the maximum distance between the 125 co-operating pairs of drawing rollers, a sec-

ond conveyor for receiving the sections from said first mentioned conveyor and movable in a direction at right angles to the conveying movement of the first mentioned conveyor for 5 delivering the sections endwise, and breaking means receiving the sections endwise from said second mentioned conveyor.

4. An apparatus for making fiber material from stalks including means for delivering 10 stalks sidewise, means for cutting the stalks into sections during said sidewise movement, and of a length less than the maximum distance between the cooperating pairs of drawing rollers, breaking means for said sections, 15 and means for delivering the sections endwise to said breaking means from said first mentioned means.

5. An apparatus for making fiber material from stalks, comprising apparatus for separating the fiber material from the stalks, a 20 pair of endless conveyer tapes having cooperating conveying branches and each composed of a plurality of parallel sectional tapes, driving means for said tapes, and saws 25 intersecting the said cooperating branches and disposed between the sectional tapes thereof.

6. An apparatus for making fiber material from stalks, comprising apparatus for separating the fiber material from the stalks, a 30 pair of endless conveyer tapes having cooperating conveying branches tapering from the inlet end to the delivery end and composed of a plurality of parallel sectional 35 tapes, driving means for said tapes, and saws intersecting the said cooperating branches and disposed between the sectional tapes thereof.

7. An apparatus for making fiber material 40 from stalks, comprising apparatus for separating the fiber material from the stalks, a pair of endless conveyer tapes having cooperating conveying branches tapering from the inlet end to the delivery end and each 45 composed of a plurality of parallel sectional tapes, driving means for said tapes, a table disposed below and in position for supporting the lower one of the said cooperating branches, and saws intersecting the said table and cooperating branches and disposed between the sectional tapes thereof.

8. An apparatus for making fiber material 50 from stalks, comprising apparatus for separating the fiber material from the stalks, a 55 pair of endless conveyer tapes having cooperating conveying branches tapering from the inlet end to the delivery end and each composed of a plurality of parallel sectional tapes, said cooperating branches having their 60 delivery portions in close proximity, driving means for said tapes, and saws intersecting the said cooperating branches and disposed between the sectional tapes thereof.

9. An apparatus for making fiber material 65 from stalks, including a pair of endless con-

veyer tapes having cooperating conveying branches tapering from the inlet end to the delivery end and composed of a plurality of parallel sectional tapes, the distance between the portions of said cooperating branches at 70 the delivery end thereof being substantially equal to the thickness of the stalks, driving means for said tapes, and saws intersecting the said cooperating branches and disposed between the sectional tapes thereof. 75

10. An apparatus for making fiber material from stalks, including a pair of endless conveyer tapes having cooperating conveying branches composed of a plurality of parallel sectional tapes, driving means for said 80 tapes, saws intersecting the said cooperating branches and disposed between the sectional tapes thereof, two conveyer bands disposed at the delivery end of said cooperating 85 branches transversely thereof and extending from a median part of the delivery end outwardly and in position for receiving different portions of the cut stalks, and driving means for said bands adapted to move the upper branches outwardly from said tapes and 90 in opposite directions.

11. An apparatus for making fiber material from stalks, including a pair of endless conveyer tapes having cooperating conveying branches composed of a plurality of parallel sectional tapes, driving means for said 95 tapes, saws intersecting the said cooperating branches and disposed between the sectional tapes thereof, two conveyer bands disposed at the delivery end of said cooperating 100 branches transversely thereof and extending from a median part of the delivery end outwardly and in position for receiving different portions of the cut stalks, driving means for said bands adapted to move the upper branches outwardly from said tapes and 105 in opposite directions, and a rockable gate disposed below the delivery end of said tapes and in position for directing the portions of the cut stalks respectively to said conveyer 110 bands.

12. An apparatus for making fiber material from stalks, comprising endless conveyer tapes composed of a plurality of parallel sectional tapes, driving means for said tapes, 115 saws disposed between the sectional tapes thereof, two conveyer bands disposed at the delivery end of said cooperating branches transversely thereof and extending from a median part of the delivery end outwardly 120 and in position for receiving different portions of the cut stalks, driving means for said bands adapted to move the upper branches outwardly from said tapes and in opposite directions, and breaking means and scutching means in the form of a Crighton opener located at the delivery end of one of said 125 conveyer bands, said scutching means comprising a foraminated casing provided internally with pins. 130

13. An apparatus for making fiber material from stalks, comprising endless conveyer tapes composed of a plurality of parallel sectional tapes, driving means for said tapes, saws disposed between the sectional tapes thereof, two conveyer bands disposed at the delivery end of said tapes transversely thereof and extending from a median part of the delivery 70 end outwardly and in position for receiving different portions of the cut stalks, driving means for said bands adapted to move the upper branches transversely thereof and extending from a median part of the delivery end outwardly and in position for receiving different 75 portions of the cut stalks, driving means for said bands adapted to move the upper branches outwardly from said tapes and in opposite directions, thrashing means at the delivery end of one of said conveyer bands, breaking, scutching and cleaning means at the delivery end of the other one of said conveyer bands, an endless conveyer band located in position for carrying the 80 thrashed pieces from said thrashing means to the intake end of said first named conveyer bands, rollers disposed one above the delivery end of said conveyer band leading to said thrashing means and another above the intake 85 end of the conveyer band leading to said breaking, scutching and cleaning means.
14. An apparatus for making fiber material from stalks, comprising conveyer members, cutting means disposed between adjacent members for subdividing the stalks into sections, two conveyer bands disposed at the delivery end of said conveyer members transversely thereof and extending from a median part of the delivery end outwardly and in position for receiving different portions of the cut stalks, driving means for said bands adapted to move the upper branches outwardly from said tapes and in opposite directions, thrashing means at the delivery end 90 of one of said conveyer bands, breaking, scutching and cleaning means at the delivery end of the other one of said conveyer bands, and means for carrying the thrashed pieces from said thrashing means to said breaking, scutching and cleaning means, 95 subdividing them at once into sections of a length less than the maximum distance between the cooperating pairs of drawing rollers, and conveying the sections endwise to and through a breaker.
15. An apparatus for making fiber material from stalks, comprising endless conveyer tapes, driving means for said tapes, saws disposed between the sectional tapes thereof, two conveyer bands disposed at the delivery end of said tapes transversely thereof and extending from a median part of the delivery end outwardly and in position for receiving different portions of the cut stalks, driving means for said bands adapted to move the upper branches outwardly from said tapes and in opposite directions, thrashing means at the delivery end 100 of one of said conveyer bands, breaking, scutching and cleaning means at the delivery end of the other one of said conveyer bands, and means for carrying the thrashed pieces from said thrashing means to said breaking, scutching and cleaning means, subdividing them into sections, delivering the sections endwise to and through a breaker, and thereafter subjecting them to the action of a scutching device.
16. An apparatus for making fiber material from stalks, comprising endless conveyer tapes, driving means for said tapes, saws disposed between the sectional tapes thereof, two conveyer bands disposed at the delivery end of said tapes transversely thereof and extending from a median part of the delivery end outwardly and in position for receiving different portions of the cut stalks, driving means for said bands adapted to move the upper branches outwardly from said tapes and in opposite directions, thrashing means at the delivery end of one of said conveyer bands, breaking, scutching and cleaning means at the delivery end of the other one of said conveyer bands, and an endless conveyer band located in position for carrying the thrashed pieces from said thrashing means to said breaking, scutching and cleaning means.
17. The method of obtaining fiber material from stalks which includes conveying the stalks sidewise past a cutting apparatus to 105 subdivide them at once into sections of a length less than the maximum distance between the cooperating pairs of drawing rollers, and conveying the sections endwise to and through a breaker.
18. The method of obtaining fiber material from stalks which includes feeding the stalks sidewise past a cutting apparatus to subdivide them into sections, delivering the sections endwise to and through a breaker, and thereafter subjecting them to the action of a scutching device.
19. The method of obtaining fiber material from stalks which includes delivering the stalks endwise, cutting them into sections during said delivery movement, moving the sections from the body of the stalk endwise in one direction and the sections formed from the top of the stalk endwise in the opposite direction, and separately treating the sections delivered in opposite directions.
20. The method of obtaining fiber material from stalks which includes cutting the stalks into sections, delivering the sections formed from the body of the stalk endwise in one direction and the sections formed from the top of the stalk endwise in another direction, freeing the second mentioned sections from seeds and leaves, and delivering the stalk parts thereof to the first mentioned sections.
21. The method of obtaining fiber material from stalks which includes cutting the stalks into sections, delivering the sections formed from the body of the stalk endwise in one direction and the sections formed from the top of the stalk endwise in another direction, freeing the second mentioned sections from seeds and leaves, delivering the stalk parts thereof to the first mentioned sections, breaking the stalks of the first mentioned sections, and exposing the stalks to stage 125.

tions together with the stalks from the second mentioned sections, and thereafter subjecting them to the action of a scutching device.

5 22. The method of obtaining fiber material from stalks which includes cutting the stalks into sections, thrashing the sections cut from the top of the stalks to free them from leaves and seeds, and delivering the stalk portions of 25 said last mentioned sections to the stalk sections formed from the body of the stalk.

10 23. The method of obtaining fiber material from stalks which includes cutting the stalks into sections, thrashing the sections cut from the top of the stalks to free them from leaves and seeds, delivering the stalk portions of said last mentioned sections to the stalk sections 30 formed from the body of the stalk, and delivering all of said stalk sections to a breaker.

15 20 24. The method of obtaining fiber material

from stalks which includes cutting the stalks into sections, thrashing the sections cut from the top of the stalks to free them from leaves and seeds, delivering the stalk portions of 25 said last mentioned sections to the stalk sections formed from the body of the stalk, and delivering all of said stalk sections endwise through a breaker, and thereafter to a scutching device.

25. The method of obtaining fiber material 30 from stalks which includes cutting the stalks into sections, thrashing the sections cut from the tops of the stalks to remove seeds and leaves, delivering the thrashed stalk sections to the unthrashed stalk sections, and treating 35 all of said stalk sections together by breaking and scutching.

In testimony whereof I hereunto affix my signature.

EMIL GMINDER.
